GEORGE EUGENE BARRETT, OF NEW YORK, N. Y., ASSIGNOR TO LENHER ENGINEERING COMPANY, OF NEW YORK, N. Y., A CORPORATION OF NEW JERSEY.

STEERING MECHANISM FOR VESSELS.

Application filed July 28, 1927. Serial No. 208,920.

My present invention refers to certain new and useful improvements in steering apparatus for vessels of various kinds, the object being to reduce and simplify the number of parts without impairing the efficiency, thus cheapening the cost of construction and operation. The improvements are peculiarly applicable to battleships, cruisers and the like, but I am by no means confined thereto, and may extend the use wherever opportunity offers.

The invention may therefore be said to consist essentially in the construction, combination, and arrangement of parts, and in numerous details and peculiarities of the same, substantially as will be hereinafter described and claimed.

In the accompanying drawings, illustrating my invention:

Figure 1 is a top plan view of my improved steering mechanism.

Figure 2 is a partial horizontal sectional plan view.

Figure 3 is a cross-section on the line 3, 3, of Figure 1.

Figure 4 is an enlarged cross-section on the line 4, 4, of Figure 1, showing especially the gear housing or casing.

Figure 5 is a detail plan view of the lower half of the housing shown in Figure 4, and certain mechanical members therein, with certain parts broken off and certain other parts in section.

Figure 6 is an enlarged partial sectional detail of a transverse portion of the said housing and one of the actuating pinions for the screw shaft gear, together with the shaft for said pinion, and the clutch mechanism for throwing one of the power devices into and out of action.

Similar characters of reference designate corresponding parts throughout all the different figures of the drawings.

1 denotes a cross-head, beam, or steering bar, which lies in a horizontal position, and oscillates to and fro on a central vertical pivot shaft 2, to which it is keyed. The rudder (not shown) is connected in any suitable manner with upright 2, and this upright 2 is supported in suitable bearings (not shown) in the stern of the vessel; but as the invention does not reside in these details, but

in the mechanism for operating the rudder or steering devices, I have thought it sufficient to illustrate the cross-head and the devices for moving the same back and forth and thus to shift the rudder into the various proper steering positions, as required from time to time. The cross-head 1 is formed with slotted ways or guides 1^a and 1^b in which slide blocks 3, 3, to which links 4, 4, are pivotally connected by pivots 5. The pull and push of the links 4 on the blocks 3 turns the cross-head 1 back and forth and controls the rudder.

At some suitable point in the vessel, in front of the cross-head 1, is a group of longitudinal members, comprising the two parallel guide rods or tubes 10, 10, and the intermediate screw shaft, also preferably tubular, having left and right hand screw sections A and B. The ends of rods 10 nearest the rudder are supported in upright standards or bearings 11, 11, and the adjacent end of screw section A is supported in the intermediate bearing 12; while the opposite ends of rods 10 and of screw B are supported in a housing or casing, having upper section 13 and lower section 14, as indicated in Figures 4 and 5.

This housing or casing for the ends of the rods 10, the screw shaft, and for various gears to be presently described, is an important feature of my invention, and I desire to broadly protect the same. It may be made of any number of parts, but I prefer to construct it of two main sections, the upper one 13, and the lower one 14, which are securely bolted together, the bolts passing through horizontal flanges that rest on each other, as shown in Figures 4 and 5. The housing stands upright and the space between its vertical walls is narrow so that the casing is relatively thin, but wide enough to accommodate the gears therein, and to furnish the necessary supports and bearings. The outside surfaces of the housing walls may have any desired number of flanges, angle irons, ribs, supporting feet, etc., and may be provided with plates, covers, man-holes or other features to allow shafts, rods, and the actuating screw to enter it, and in order to adapt it for the work and duties which it is intended for. As already stated, the ends of

2 rods 10 and screw B have supports in this housing. By referring to Figures 4 and 5 it will be seen that in the housing the ends of rods 10 have a reduced section 10^a between an outer flange 10^b and an inner shoulder 10^c, which reduced section 10^a serves as a supporting end of the rod carried firmly in the wall of the housing between the two sections of said housing. And further the smooth end portion B¹ of screw B in the housing omits its thread far enough to provide this smooth section B¹ to serve as a journal on which the screw shaft may revolve, as also to carry a gear wheel 15 keyed rigidly thereto, which gear wheel is protected inside of the housing. The section B¹ revolves in bushings in the vertical walls of the housing at both sides of gear wheel 15. This gear wheel 15 is engaged by the two pinions 16, 16, said gear and pinions being protected within the housing, which is filled with oil to lubricate the gearing and the various bearings and other parts.

25 The right and left hand screw A, B, is a single shaft, preferably tubular for the sake of lightness and strength, one half of which, as A, is a left hand screw, and the other half of which, as B, is a right hand screw. A short middle part of the screw 30 where the right and left threads meet is left plain to form a bearing journal that rotates in the bearing 41 that is midway between the end bearing 12 and the bearing in the housing. This center bearing 41 not only prevents sag in the relatively long screw shaft, but enables the screw shaft to be stiffer, and hence a diametrically smaller one may be used than otherwise, thus saving in cost of material as well as promoting reliability of 35 operation.

40 On each rod 10 is a long sliding sleeve 7, consisting of an elongated tubular member, as shown in Figure 2. The ends of these sleeves towards the cross-head 1 are formed with right angled arms 6, to which the actuating links 4, 4, are pivotally connected by pivot pins 8, the ends of arms 6 being slotted as seen in Figure 3 to receive the perforated ends of links 4. Further, one sleeve 45 7 carries an internally threaded nut 9 on the end adjoining its arm 6, said nut consisting of a casting bolted to the sleeve, which nut engages the screw threaded section A; and the other sleeve 7, on its end farthest from its 50 arm 6 has a similar internally screw threaded nut 9^a that consists of a casting bolted to the sleeve and this nut engages the thread of screw section B. Thus when the 55 right and left screw A, B, rotates, the nuts 9 and 9^a will be caused to travel towards or away from each other in opposite directions on the respective screw sections A and B, and the sleeves 7 will slide also in opposite directions on their guide rods 10, and the result 60 65 will be that one link 4 will pull on one end

of cross-head 1, and the other link will push on the other end of cross-head 1 so that the combined action of the two links will be to turn the cross-head and its rudder about a greater or less distance as required in steering. 70

Each elongated sleeve member 7 has internal end bushings, see Figure 2. Thus near the left hand end is bushing 44, packed by a packing held in place by gland 42; and at the opposite end is bushing 45, packed by a packing held in place by gland 43. In addition to these end bushings there is a middle bushing 26 held in place by screw bolts 27. This middle bushing gives the long sleeve 80 a central support on its guide rod, and enables a severe bending strain to be given to the rod without buckling or bending it, thus giving better steering results, with less injury to the machinery. At certain times and in certain positions of the sleeves, corresponding to certain positions and movements of the rudder, the strain on the rods and on the sleeves, is very great, and I aim to reinforce the parts and enable them to better withstand this strain. The interior of the sleeves provides an annular oil space to lubricate the bushings and sleeves in their reciprocatory movements on the guide rod, 10. 90

95 The right and left screw shaft which actuates the sleeves jointly so as to move the cross-head and rudder or other steering member, is driven by a system of gearing, and the gearing is propelled by motors or 100 engines of any preferred kind. The aforesaid gearing comprises the large intermediate gear wheel 15, see Figure 4, which is keyed on the part B¹ of screw shaft section B. This gear wheel 15 is engaged by two 105 pinions 16 which operate together upon the gear wheel 15 to rotate it in the same direction, said pinions rotating in the same direction. The pinions 16 are made integral with 110 shafts having suitable clutch mechanism and operated by the motors C, C, one motor for each pinion 16. These motors C and their location relatively to the rest of the mechanism are shown in Figure 1; and the detailed parts of the shaft and clutch devices between the motors C and the pinions 16, are delineated clearly on a large scale in Figure 6. 115

120 It is manifest that the driving machine C, C, may be any kind of motors, as steam, gas, electric or any other kind; or they may be driving pumps arranged to impart rotary motion to their parallel shafts 17, 17. These motors are duplicate and operate in the same manner to rotate their shafts in the same direction, and both are normally actively in clutch at all times, and it is not intended ordinarily to throw either out of clutch. The cutting out of either motor is only done 125 when said motor goes dead in consequence of some injury or breakdown, in which case it 130

will be cut out and the whole load or duty will be necessarily thrown over on to the other motor.

Referring to the detailed parts best shown in Figure 6, it will be seen that a clutch member 18 constructed in any desired way and of as many parts as preferred and having teeth 19 is keyed to the motor shaft 17. This clutch member 18 extends over the aligned shaft section 24 and revolves on a bushing or sleeve 46 held in place between a disk 37 bolted on the end of shaft section 24 by a bolt 38 and a packing ring 47 which lies between the sleeve 46 and the keys 23 rigid in section 24, on which keys 23 the movable clutch member 20 slides. This movable member has teeth 21 adapted to engage teeth 19 on the clutch member 18 that is secured to motor shaft 17; and a lever 39 pivoted at 40 has pins or other devices engaging the circular groove 22 in the sliding clutch section 20. Therefore by manipulating the handle 39 the clutch member 20 can be thrown into or out of engagement with the clutch member 18, and the power of the revolving motor shaft 17 transferred to or cut off from the shaft 24. Obviously both motor mechanisms have similar clutch devices easily operated by lever handles as 39.

The shaft section 24 for each motor driving appliance is integral with another shaft section 25 with which the pinion 16 is made integral, the teeth of which pinion 16 engaged the large driving gear wheel 15. Shaft section 25 is supported within the lower housing section 14 in two ball bearings 32 and 33 in the sidewalls of the housing, adjacent to openings therein which are fitted with covers 28 and 34, cover 28 being secured to the housing by bolts 30, which also hold a packing gland 29 that compresses an inner packing. And cover 34 is secured in place by bolts 35. The ends of shaft section 25 are suitably reduced in diameter to carry the inner race-ways of the ball bearings, the inner race of ball bearing 33 being held firmly on the end of the shaft by a bolted disk 36; and the inner race of the bearing 32 being held firmly on shaft 25 by a screw washer 31 binding against it and screwing on a few threads on section 24 where it merges into section 25. Of course these details may vary widely and I give them by way of illustration. It may be noted quite obviously that a similar combination is provided between each motor C and the pinion 16 driven thereby, these constructions being duplicates in every respect, for the purpose of enabling each motor to be connected with a similar pinion which engages and drives the large gear wheel and the screw shaft, so that at one time when both motors are functioning both pinions will be exerting the same kind of a rotary effect upon the large gear, and when only one motor is functioning the pinion

driven by it will be exerting the same kind of an effect on the large gear wheel, whereby at one time the gear is driven by two pinions and at another by one pinion, but the drive is of the same kind.

In the operation, the motors will run simultaneously, both clutch mechanisms being in engagement, with the result that the two pinions both jointly drive the gear wheel 15. If one motor ceases to operate for any cause, the attendant may throw the clutch lever 39 belonging to that particular motor and unclutch it from the rest of the mechanism, after which the other motor will have to do all the work of steering; but the single pinion 16 in this case will do the same work previously done by both pinions when both motors were actively running. By a simple quick movement of one or the other of the clutch levers, a broken or incapacitated motor is cut out of operative connection with the other parts so that it will not interfere with the working of the companion motor.

Many changes in the details and in the construction and arrangement of parts may be made within the limits of the appended claims.

What I claim is:

1. In mechanism of the class described, the combination with a rudder cross-head, of parallel guide rods, a right and left hand screw shaft between the rods, means for supporting the rods and screw at one end, a housing for enclosing and supporting the opposite ends of the rods and screw, elongated sliding sleeves on the guide rods having internally threaded members that engage the screw and having also projecting arms, links pivoted to said arms and to the cross-head, gearing within the housing, and a dual power mechanism for actuating the gearing, together with means for throwing either half of said power mechanism out of action.

2. In mechanism of the class described, the combination with a rudder cross-head, of parallel guide rods, a screw intermediate of said rods and having a left hand thread and a right hand thread, means for carrying the rods and the screw at their ends, permitting rotating of the screw, a bearing also at the center of the screw between the right and left threads, elongated sliding sleeves on the guides, one on each, said sleeve having annular interior oil chambers together with end bushings and a central supporting bushing to facilitate movement on the rods, one of said sleeves having a nut engaging the left thread of the screw and the other sleeve having a nut engaging the right thread of the screw, and both of said sleeves having arms, links connecting the arms with the opposite ends of the cross-head, and power mechanism for rotating the screw.

3. In mechanism of the class described,

- the combination with a rudder cross-head, of longitudinal guide rods and a screw between them, said screw having right and left hand threaded sections, traveling sleeves on the rods having threaded members engaging the screw, means connecting the sleeves with the cross-head, means for supporting the rods and screw at one end and providing a bearing for the screw at that end, means for supporting the rods and screw at the other end and providing a bearing for the screw at that end, said latter means consisting of a housing, a gear within the housing and on the screw, two pinions within the housing and engaging the gear wheel, shafts carrying said pinions, twin power devices, one for each of said shafts, and clutch mechanisms for the power devices for placing the same in or out of action.
4. In mechanism of the class described, the combination with a rudder cross-head, of longitudinal guide rods and a screw between them, said screw having right and left hand threaded sections, traveling sleeves on the rods having threaded members engaging the screw, links connecting the sleeves with the cross-head, means for supporting the rods at one end and providing a bearing for the screw at that end, means for supporting the rods and screw at the other end and providing a bearing for the screw at that end, said latter means consisting of a housing in which reduced end portions of the rods are secured and in which the journal end of the screw rotates, a drive gear wheel secured on this end of the screw and enclosed by the housing, two pinions within the housing engaging the gear wheel, shafts carrying said pinions, ball bearings in the walls of the housing for said pinion shafts, twin motors for jointly actuating the pinions, and a clutch clutch mechanism for each motor to throw it into or out of action.
5. In mechanism of the class described, the combination with a rudder cross-head, of longitudinal guide rods and a screw between them, said screw having right and left hand threads, traveling sleeves on the rods having nuts engaging the screw, links connecting the sleeves with the cross-head, supports for the rods at one end, a bearing for the screw at the same end, a housing or casing of two main parts providing a support for the other ends of the guide rods, and a bearing for the other end of the screw, a gear wheel within the housing and secured on the screw, a pair of pinions engaging the gear wheel within the housing, separate parallel shafts for the pinions, bearings for mounting said pinion shafts in the housing, a motor for each of said shafts having itself a shaft, and a clutch device for each motor having a member on the motor shaft and an interlocking member on the pinion shaft, all arranged so that both motors

may jointly actuate the screw in the same direction.

6. In mechanism of the class described, the combination with a cross piece, of parallel guide rods and a right and left screw, traveling sleeves on the rods having nuts engaging the screw, and having arms, links pivoted to said arms and to the cross piece, a housing or casing having two main parts, an upper and a lower, said lower part having cover-provided shaft-receiving openings, the walls of said housing receiving and supporting one of the reduced and flanged ends of the rods and also providing a bearing for one of the screws, a train of gears within the housing for actuating the screw, one being on the screw, and the other two engaging that one, shafts carrying the latter two gears and supported in bearings in the aforesaid shaft-receiving openings, together with power mechanism for driving both of said shafts or only one of them.

7. In mechanism of the class described, the combination with an oscillatable cross beam, of guide rods, a screw between them, nuts traveling on the screw, sleeves connected to said nuts and traveling on the rods, connections between the sleeves and the cross beam, supporting means at one end of the rods and screw, and a casing at the other ends of the rods and screw to provide a support for the rods and a bearing in which the screw may rotate, said casing consisting of an upper shell and a lower shell, with vertical walls relatively narrowly-spaced apart, said walls being oppositely apertured at points to permit shafts to enter, and a train of gears in said casing, one gear of the same being on the screw, and two pinions of the same engaging the gear, and parallel shafts entering the aforesaid apertures and carrying the pinions, together with power mechanism to drive the gear mechanism, and means to cut out one or the other of the pinions from the gear train.

8. In a rudder control, an oscillatable member, in combination with a right and left screw shaft for oscillating it, mechanism interposed between the screw shaft and the oscillatable member, comprising sleeves with nuts engaging the screw, guides for the sleeves, and connections between the sleeves and the oscillatable member, and mechanism for rotating the screw shaft consisting of a dual motor device and gearing between same and the screw shaft, a lubricant-containing housing for said gearing, and means for enabling the dual motor device to function as a single motor device.

9. In a rudder control, the combination with the cross-head, of guide rods, a right and left screw, tri-bushed sleeves sliding on the guide rods and having threaded nuts engaging the screw, links pivoted to the

cross-head and to the sleeve, a bearing for one end of the screw, a central bearing for the screw, a bearing for the other end of the screw, a gear wheel on the latter end of the screw, a pinion engaging the gear wheel, a housing covering the gearing and supporting the last-mentioned screw bearing, a sec-

tional shaft for the pinion, the sections having coupling and upcoupling means, and power mechanism to drive the pinion shaft. 10

In testimony whereof I hereunto affix my signature.

GEORGE EUGENE BARRETT.
